UNITED STATES PATENT OFFICE.

ESTEL C. RANEY, OF COLUMBUS, OHIO.

AUTOMATICALLY-RECLOSING CIRCUIT BREAKER.

Application filed May 9, 1923. Serial No. 637,816.

To all whom it may concern:

Be it known that I, ESTEL C. RANEY, a citizen of the United States of America, residing at Columbus, in the county of Franklin and State of Ohio, have invented certain new and useful Improvements in Automatically-Reclosing Circuit Breakers, of which the following is a specification.

My invention relates to automatically reclosing circuit breakers and has to do particularly with the provision of a peculiarly sensitive reclosing mechanism that is nevertheless fully guarded against any operation except when the proper conditions exist for the closing of the breaker.

Briefly stated, I have provided a means for controlling reclosure of the breaker of such a nature that the breaker will be locked against reclosure as long as a short circuit exists regardless of fluctuation of the supply or line voltage and yet be operative whenever the short circuit is removed sufficiently so that the load voltage reaches a predetermined value.

Another important aspect of my invention consists in the fact that it is operable automatically from either side. In other words, it makes no difference whether the current is supplied from one side of the breaker or the other or whether it is supplied from both, reclosing will be effected automatically when the short circuit is removed and the load voltage reaches a predetermined amount.

One specific form of my invention consists in the provision of a controlling means that is maintained inoperative by electrically maintaining it in a state of balance or equilibrium and that can only be operative by disturbing such balance or equilibrium with the result that an extreme of sensitivity is attainable, while a means is provided for precluding operation to reclose the breaker until a definite load voltage exists.

In the form shown, the balanced condition is produced by two coils which are so wound and connected that they balance each other as long as a short circuit exists but are thrown out of balance upon the removal of the short circuit, because of the fact that the increased load resistance automatically operates to effect an increase of voltage being applied to one of said coils and the simultaneous decrease of the voltage being applied to the other of said coils.

The two coils in question are electromag-

nets which operate upon armatures carried upon a pivoted switch element and serve to prevent closing of this switch element when they are balanced electrically, that is, when the short circuit exists. Complemental to this structure, is an adjustable spring element and an adjustable stop for purposes to be described. This structure is adjustable to ensure that the breaker will reclose whenever a voltage of a predetermined value arises in the load circuit.

The preferred form of my invention is shown in the accompanying drawings wherein similar characters of reference designate corresponding parts and wherein

Figure 1 is a view of an automatically reclosing circuit breaker with a complete diagram of circuit connections for the operation of the present invention and showing the condition of circuits with the breaker closed.

Figure 2 is a diagram showing the circuits of the controlling device under short circuit conditions.

Figure 3 is a simplified diagram omitting the circuits of the circuit breaker and illustrating the condition of the circuit when 600 volts potential exists between feeders A and C and a short circuit exists between feeders B and C.

Figure 4 is a diagram like Figure 3 except that it is assumed that the short circuit has been removed and a load resistance of .69 ohms is connected between feeders B and C.

Figure 5 is a diagram like that of Figures 3 and 4, except that it is assumed that the line or supply voltage is reduced to 400 volts while a short circuit exists between feeders B and C.

Figure 6 is a diagram like that in Figure 5, except that it is assumed that the load resistance has increased to 1.05 ohms between feeders B and C.

Figure 7 is a diagram illustrating the application of my improvement to a three wire system of distribution.

In the drawings, I have shown my invention applied to an electrically operated circuit breaker mechanism in which the connections are so made that the breaker will operate when used either in a system where the breaker is used to supply current in one direction only, or where the current is fed in one direction at times and in opposite di-

rections at other times, or where the breaker is used to connect two sections independently supplied.

Referring specifically to Figures 1 and 2, a main contact element 1 is nominally held in contact with terminals 2 and 3 by the action of a coil 4. In the event of a short circuit or overload, the overload coil 5 opens the circuit of the coil 4 by lifting the contact 6. This results in the immediate opening of the main contact 1 and the closing of the coil 7 through the contact 8. Coil 7 in turn closes the contact 9 after a delay of a time interval due to the retarding action of dash-pot 10 or an equivalent device.

When the breaker is thus opened, the main terminals thereof are bridged by a resistance element formed in two equal sections D and E, connected together at K. The controlling means for the reclosing mechanism comprises coils 17 and 18.

Figure 2 shows the circuits after a short circuit has caused the breaker to open, and the time interval provided by dash-pot 10 has elapsed. The closing coil 4 has a resistance element 11 interposed in its circuit of such value as to reduce the current in coil 4 below the value necessary to effect reclosure, but of sufficient value to maintain contact 1 closed after reaching the closed position.

The reclosure of the breaker is dependent upon the operation of switch mechanism 12 to close the circuit, thus shunting out coil 11 and subjecting coil 4 to an operative potential.

Switch 12 is operated by the movement of a non-magnetic bar pivoted at 14, and carrying an armature at either end as 15 and 16, which are under the influence of coils 17, and 18. An adjustable stop 19 is provided so that armatures 15 and 16 may be adjusted equidistant from coils 17 and 18 in order that they will be equally attracted when coils 17 and 18 are subjected to equal voltages. An adjustable spring 20 is also used to regulate the voltage necessary to close the switch 12.

Coil 17 is connected to points K which is the mid point of the two equal resistance elements D and E, coil 18 is connected in parallel to the resistance element D and therefore subjected to the same potential as exists between A and K.

Since resistance sections D and E are equal and connected across the breaker terminals when short circuit has opened the breaker, it will be obvious that as long as this short circuit continues the potentials between A and K, K and B, and K and C will be equal.

Therefore, so long as a short circuit exists between conductors B and C an equal voltage will be impressed on coils 17 and 18, this voltage being one half that existing be-

tween A and C. While equal pulls are exerted by coils 17 and 18 there will be no movement of switch 12, however when the pull of coil 17 becomes stronger than that of coil 18 due to the removal of the short circuit and a resultant increase of potential between B and C to a predetermined value, armature 15 will be moved toward coil 17, resulting in the closure of switch 12, and the final closure of main contact 1, by action of coil 4.

At the instant of closure of contact 1, the contact 8 will open the circuit of coil 7, which in turn opens contact 9 and de-energizes coil 17, resulting in the introduction of resistance 11 again in the circuit of coil 4.

The functioning of my controlling device, under a short circuit condition, is clearly illustrated in Figure #3, in which case we have assumed a potential of 600 volts existing between feeders A and C. Since a short circuit exists between feeders B and C, the potential between sections A and B will also be 600 volts. Since resistance elements D and E are equal and coils 17 and 18 have an equal resistance, there will be a potential difference of 300 volts between points A and K and K and B. Also since B and C are of the same potential there will be a potential of 300 volts between points K and line C. It is thus apparent that so long as a short circuit condition exists coils 17 and 18 will each have an equal voltage applied to them and the non-magnetic bar will be balanced since an equal attraction will exist on armatures 15 and 16 so that switch 12 will not be operated.

In Figure #4 we have assumed the same potential existing between feeders A and C but in this case it is assumed that the short circuit has been removed and the load resistance increased to such a value that the current by-passed around the open breaker thru resistance D and E will raise the potential between lines B and C to 20 volts. In this case the difference of potential between sections A and B is reduced to 580 volts and since coils 17 and 18 are of equal resistance and the resistance of coils 17 and 18 is very high as compared to that of D and E, this potential of 580 volts will be practically equally distributed between resistance sections D and E. Therefore it may be assumed for practical purposes that the drop of potential from section A to point K is 290 volts, which, subtracted from 600 volts, leaves a drop of potential between point K and line C of 310 volts. It is thus evident that coil 17 will now be subjected to a potential of 310 volts while coil 18, being connected directly in parallel with resistance section D which has a potential drop of 290 volts, the potential applied to coil 18 will be identical to that of resistance D or in this instance 290 volts. It is now

apparent that coil 17 is subjected to a higher voltage than coil 18 by an amount of 20 volts. In this illustration we have assumed that the tension of spring 20 is so adjusted 5 that contact 12 will close when the difference in the voltages supplied to the two coils 17 and 18 is 20 volts. The operation of this switch will then shunt out the resistance 11, Figure 1, and apply operative voltage to 10 coil 4. These conditions therefore represent an operative condition.

Referring further to Figures 5 and 6, we will show that the breaker in this case will also be operative when the load resistance is 15 of such a value as to cause a potential of 20 volts to exist between sections B and C although the potential existing between section A and C in each of these figures is assumed to be 400 volts instead of 600 volts 20 as was the case in Figures 3 and 4.

Referring particularly to Figure #5 we have assumed that a difference of potential of 400 volts exists between sections A and C and since a short circuit connects B and 25 C, making them of the same potential, there will also be a difference of potential between A and B of 400 volts. Assuming, as before, that this potential difference is equally divided between sections D and E, each of 30 these sections will have a potential drop of 200 volts. Therefore there will also be a potential drop of 200 volts between point K and line C. In this case it is noticed that coil 17 and 18 are each subject to an equal 35 potential of 200 volts.

In Figure #6 it is assumed that the load resistance has increased to such a value as to produce a potential difference of 20 volts between B and C due to flow of current thru 40 resistance sections D and E, and the load resistance. In this case since there is 20 volt drop between B and C and 400 volts between A and C the potential existing between section A and B is now reduced to 45 380 volts, one-half of which occurs in section D and one-half occurring in section E. Since there is a drop of potential of 190 volts between points A and K there will exist a potential difference between K and C 50 of 400 volts minus 190 volts, or 210 volts. It is now apparent that coil 17 is subjected to a potential of 210 volts while coil 18 has only 190 volts potential. These coils will therefore have an unbalanced attraction 55 on pivoted bar of switch 12 and with the same tension of the spring 20 as was assumed previously, the contact switch 12 will be closed and cause the operation of the breaker.

60 It can be similarly demonstrated that for any chosen value of potential between sections A and C that coils 17 and 18 will be in balance or subject to the same voltage so long as a short circuit exists between section B and C, and for any condition other

than a short circuit the difference of voltage applied to coils 17 and 18 will be equal to the difference of potential existing between B and C. This is due to the fact that coil 17, being connected midway between A and 70 B, the increase of potential from K to C will be one-half as much as the increase of potential between B and C. Also the decrease of potential across section D will always be one-half of the decrease of potential 75 between A and B, thus making the difference in potentials applied to coils 17 and 18 equal to the potential between section B and C.

Figure 7 shows the application of this 80 scheme of control to a three wire system of distribution. The coils 17 and 18 in this case control the reclosing mechanism of the breaker so that the breaker is held open regardless of fluctuation of the supply voltage so long as 85 a short circuit exists between any two wires, the breaker being closed however whenever load voltage rises to a predetermined voltage by removal of the short circuit. For the sake of clearness other operating details 90 have been omitted and only the principal connections shown which constitute the principal part of this invention.

It is apparent that I have provided a controlling means for automatically governing 95 the reclosure of an automatically reclosing circuit breaker which will not be affected by fluctuations of supply voltage as long as the short circuit remains. It will also be obvious that the device being in a state of 100 balance can be made extremely sensitive in operation after the short circuit is removed.

It is further apparent from the foregoing description that this apparatus is perfectly reversible in its operation on account 105 of the symmetry of connections and resistance values and that if sections A and C were to become the load sections while that of B and C were the supply section, the breaker would still operate to lockout on shortcircuit between sections A and C and would be governed in its reclosing in the same manner as heretofore described.

While the foregoing describes my favorite 110 method of utilizing this principle I would not wish to limit the scope of this invention to the specific arrangement shown in the diagram as it is apparent that equivalent results could be obtained without departing 115 from the principle of my invention by connecting coil 18 to a point other than K and changing the proportion of the lever arm of the switch 12 from its central position, or by changing the relative resistance values of 120 coils 17 and 18, or in fact by numerous arrangements not necessary to describe herein.

125 It will be obvious that that winding 18 which is shown connected in parallel with a portion of the resistance D—E can be so ar-

ranged that it will be connected in parallel with all or any portion of said resistance without departing from my invention. In the event that this change were made, the 5 windings 17 and 18 could be so proportioned as to compensate for this alteration in connections so that the same results can be obtained.

Having thus described my invention, what 10 I claim is:

1. An automatically reclosing circuit breaker mechanism comprising a main contact member, main terminals, means for bridging said main terminals by a resistance 15 element when said main contact member is open, means for governing the reclosure of said member having one winding connected to substantially the mid point of said bridging resistance and having a second winding 20 connected in parallel with a portion of said bridging resistance.

2. An automatically reclosing circuit breaker mechanism comprising a main contact member, main terminals, means for bridging said main terminals by a resistance 25 element when said main contact member is open, means for governing the reclosure of said member having one winding connected to substantially the mid point of said bridging resistance and having a second winding 30 connected in parallel with substantially one half of said bridging resistance.

3. An automatically reclosing circuit breaker mechanism comprising a main contact member, main terminals, means for bridging said main terminals by a resistance 35 element when said main contact member is open, means for governing the reclosure of said member having one winding connected to substantially the mid point of said bridging resistance and having a second winding 40 connected in parallel with a portion of said bridging resistance and a switch held open by said windings when short circuit exists.

4. An automatically reclosing circuit breaker mechanism comprising a main contact member, main terminals, means for bridging said main terminals by a resistance 45 element when said main contact member is open, means for governing the reclosure of said member having one winding connected to substantially the mid point of said bridging resistance and having a second winding 50 connected in parallel with a portion of said bridging resistance, and a switch so related to said windings that it will be automatically closed when the short circuit is removed to a predetermined degree.

5. An automatically reclosing circuit 55 breaker mechanism comprising a main contact member, main terminals, means for bridging said main terminals by a resistance element when said main contact member is open, means for governing the reclosure of said member having one winding connected

to substantially the mid point of said bridging resistance and having a second winding connected in parallel with a portion of said bridging resistance, a switch held open by 70 said winding when short circuit exists regardless of the fluctuation of supply voltage.

6. An automatically reclosing circuit breaker mechanism comprising a main contact member, main terminals, means for bridging said main terminals by a resistance 75 element when said main contact member is open, means for governing the reclosure of said member having one winding connected to substantially the mid point of said bridging resistance and having a second winding 80 connected in parallel with a portion of said bridging resistance and a switch so related to said windings that it will be automatically closed when the short circuit is removed to a predetermined degree regardless of the 85 fluctuation of supply voltage.

7. An automatically reclosing circuit breaker mechanism comprising a main contact member, main terminals, means for bridging said main terminals by a resistance 90 element when said main contact member is open, means for governing the reclosure of said member having one winding connected to substantially the mid point of said bridging resistance and having a second winding 95 connected in parallel with a portion of said bridging resistance and a switch so related to said windings that it will be held open when short circuit exists and will be automatically closed when the short circuit is removed to a predetermined degree.

8. An automatically reclosing circuit breaker mechanism comprising a main contact member, main terminals, means for bridging said main terminals by a resistance 100 element when said main contact member is open, means for governing the reclosure of said member having one winding connected to substantially the mid point of said bridging resistance and having a second winding 105 connected in parallel with a portion of said bridging resistance, a switch so related to said windings that it will be held open when short circuit exists and will be automatically closed when the short circuit is removed to a predetermined degree, and means for 110 adjusting the degree.

9. An automatically reclosing circuit breaker mechanism comprising a main contact member, main terminals, means for bridging said main terminals by a resistance 115 element when said main contact member is open, means for governing the reclosure of said member having one winding connected to substantially the mid point of said bridging resistance and having a second winding 120 connected in parallel with a portion of said bridging resistance, a switch so related to said windings that it will be automatically closed when the short circuit is removed to a predetermined degree, and means for 125 adjusting the degree.

- removed to a predetermined degree and means for adjusting the degree.
10. An automatically reclosing circuit breaker mechanism comprising a main contact member, main terminals, means for bridging said main terminals by a resistance element when said main contact member is open, means for governing the reclosure of said member having one winding connected to substantially the mid point of said bridging resistance and having a second winding connected in parallel with a portion of said bridging resistance and a switch so related to said windings that it will be held open when short circuit exists and will be automatically closed when the short circuit is removed to a predetermined degree regardless of the fluctuation of supply voltage.
11. An automatically reclosing circuit breaker mechanism comprising a main contact member, main terminals, means for bridging said main terminals by a resistance element when said main contact member is open, means for governing the reclosure of said member having one winding connected to substantially the mid point of said bridging resistance and having a second winding connected in parallel with a portion of said bridging resistance, a switch so related to said windings that it will be held open when short circuit exists and will be automatically closed when the short circuit is removed to a predetermined degree regardless of the fluctuation of supply voltage and means for adjusting the degree.
12. Means for controlling the reclosing of an automatically reclosing circuit breaker comprising windings automatically responsive to a definite difference in relative potentials of said windings.
13. Means for controlling the reclosing of an automatically reclosing circuit breaker comprising windings unresponsive to fluctuation of supply voltage but responsive to a definite difference in relative potentials of said windings.
14. Means for controlling the reclosing of an automatically reclosing circuit breaker comprising windings automatically responsive to a definite difference in relative potentials of said windings, and means for adjusting the degree of difference necessary before operation of the controlling means occurs.
15. Means for controlling the reclosing of an automatically reclosing circuit breaker comprising windings unresponsive to fluctuation of supply voltage but automatically responsive to a definite difference in relative potentials of said windings, and means for adjusting the degree of difference necessary before operation of the controlling means occurs.
16. A means for controlling the reclosing of an automatically reclosing circuit breaker of such a nature and so arranged and connected that, whichever main breaker terminal is connected to the load circuit, the breaker will reclose whenever the potential of the load side of the breaker is raised to a predetermined value irrespective of voltage fluctuations on the supply side.
17. An automatically reclosing circuit breaker mechanism having its main terminals bridged by a resistance element, a reclosing mechanism of such a nature and so arranged and connected that when either main breaker terminal is connected to a load circuit and the other main terminal is connected to a source of supply, the breaker will reclose whenever the potential of the load side of the breaker is raised to a predetermined value, irrespective of voltage fluctuations on the supply side.
18. An automatically reclosing circuit breaker mechanism having a reclosing mechanism of such a nature and so arranged and connected that when either main terminal of the breaker is connected to a load circuit and the other main terminal is connected to a source of supply that the controlling means will be equally effective to lock out on short circuit irrespective of voltage fluctuations on the supply side and to cause reclosure of the breaker whenever the potential of the load side of the breaker is raised to a predetermined value.
19. An automatically reclosing circuit breaker comprising a main contact member, reclosing mechanism, and a controlling means comprising balanced coils which are subject to equal voltages regardless of variation in line voltage as long as a short circuit exists but which are subject to different voltages when the short circuit is removed to effect the operation of said reclosing means.
20. An automatically reclosing circuit breaker comprising a main contact member, reclosing mechanism, a controlling means comprising balanced coils which are subject to equal voltages regardless of variation in line voltage as long as a short circuit exists but which are subject to different voltages when the short circuit is removed to effect the operation of said reclosing means and means for determining the degree of unbalance necessary for operation of said controlling means.
21. An automatically reclosing circuit breaker comprising a main contact member, reclosing mechanism, a controlling means comprising balanced coils which are subject to equal voltages regardless of variation in line voltage as long as a short circuit exists but which are subject to different voltages when the short circuit is removed for the operation of said reclosing means and a switch operated by said coils when unbalanced to bring about operation of said reclosing means.

22. An automatically reclosing circuit breaker comprising a main contact member, reclosing mechanism, a controlling means comprising balanced coils which are subject to equal voltages regardless of variation in line voltage as long as short circuit exists but which are subject to different voltages when the short circuit is removed for the operation of said reclosing means, and a switch operated by said coils when unbalanced to bring about operation of said reclosing means, said switch being adjustable as to the degree of unbalance necessary for operation.
23. A controlling means for an automatically reclosing circuit breaker comprising windings which are subject to voltages which remain proportional regardless of variation in line voltage as long as a short circuit exists but which proportion is changed as soon as short circuit is removed, this change of relative voltage being effective when at a given amount to cause closing of a switch.
24. An automatically reclosing circuit breaker comprising a main contact member, reclosing mechanism governed automatically by circuit conditions, said mechanism being such that it will remain inoperative as long as short circuit exists regardless of fluctuation of supply voltage but will become operative when short circuit is removed to a predetermined degree, means for adjusting said degree, and means for rendering said control operative by potential applied to either terminal of said breaker.
25. An automatically reclosing circuit breaker comprising a main contact member, reclosing mechanism, and a plurality of windings for governing said reclosing mechanism, said last windings being so arranged and connected that removal of a short circuit automatically decreases the voltage applied to one winding and increases the voltage applied to another winding.
26. An automatically reclosing circuit breaker comprising a main contact member, reclosing mechanism, and a plurality of windings for governing said reclosing mechanism, said last windings being so arranged and connected that removal of a short circuit automatically changes the relations between voltages being applied to said windings.
27. A controlling means for an automatically reclosing circuit breaker, having its windings so connected that it is inoperative so long as a short circuit exists regardless of voltage fluctuations on the supply side of the breaker and regardless of which terminal of the breaker is connected to the supply side.
28. An automatically reclosing circuit breaker mechanism having its main terminals bridged by a resistance element, a controlling means so connected that when either main breaker terminal is connected to a load circuit and the other main terminal is connected to a source of supply, the controlling means will be equally effective to lock out on short circuit and to cause reclosure of the breaker whenever the potential of the load side of breaker is raised to a predetermined value, irrespective of voltage fluctuations on the supply side.
29. An automatically reclosing circuit breaker comprising a main contact member, reclosing mechanism, a resistance across the main contact member when the breaker is open, and means for governing said reclosing mechanism, said governing means having two windings, one of which is connected in parallel with a portion of said resistance, and the other winding connected so as to form a parallel circuit to a portion of said resistance and the load.
30. An automatically reclosing circuit breaker comprising a main contact member, reclosing mechanism, means for governing said reclosing mechanism, and means for neutralizing the action of said governing means, when short circuit exists and of permitting it to operate when the short circuit is removed to a predetermined degree and means for so connecting said governing and neutralizing means that they will be equally responsive in operation, regardless of which side of the breaker constitutes the load side.
31. An automatically reclosing circuit breaker comprising a main contact member, reclosing mechanism, a coil for controlling the operation of said reclosing mechanism, a resistance across the main contact member when the breaker is open, means for governing said controlling coil, and means for neutralizing the effect of said controlling coil when short circuit exists and permitting it to operate when the short circuit is removed to a predetermined degree, and means for so connecting said governing and neutralizing means that they will be equally responsive in operation, regardless of which side of the breaker constitutes the load side.
32. A controlling means for an automatically reclosing circuit breaker having a plurality of windings so arranged and connected that the actions of said windings are neutralized so long as a short circuit exists, and means for so connecting said controlling means that it will be equally responsive in operation, regardless of which side of the breaker constitutes the load side.
33. A controlling means for an automatically reclosing circuit breaker having a plurality of windings so arranged and connected that the actions of said windings are neutralized so long as a short circuit exists, said windings being correspondingly affected by voltage fluctuations of the supply current, and means for so connecting said controlling means that it will be equally responsive in operation, regardless of which side of the breaker constitutes the load side.

responsive in operation, regardless of which side of the breaker constitutes the load side.

34. Means for governing the reclosing of an automatically reclosing circuit breaker,

5 comprising a winding whose action is to effect the closure of the breaker, another winding whose action is to restrain the action of the first mentioned winding so long as a short circuit exists, and means for so 10 connecting said windings that they will be equally responsive in operation, regardless of which side of the breaker constitutes the load side.

35. Means for governing the reclosing of 15 an automatically reclosing circuit breaker comprising a winding whose action is to effect the closure of the breaker but whose action is restrained by another winding so long as a short circuit exists, the action of 20 said windings being proportionally affected by voltage variations.

36. A means for controlling the reclosing of an automatically reclosing circuit breaker of such a nature and so arranged and connected that, whichever main breaker terminal is connected to the load circuit, the breaker will reclose whenever the potential of the load side of the breaker is raised to a predetermined value irrespective of voltage 25 fluctuations on the supply side, and means for adjusting to vary the voltage required.

37. In a system of electrical distribution, an automatically reclosing circuit breaker, a controlling means comprising a plurality of 35 windings, one of which is subject to an increase of potential and the other of which is subject to a decrease of potential as the short-circuit is removed.

38. In a system of electrical distribution, 40 an automatically reclosing circuit breaker, a controlling means comprising a plurality of windings, one of which is subject to an increase of potential and the other of which is subject to a decrease of potential as the

short-circuit is removed, said means being 45 so connected that the voltage impressed on such windings is increased as the supply voltage increases.

39. In a system of electrical distribution, 50 an automatically reclosing circuit breaker, a controlling means comprising a plurality of windings, one of which is subject to an increase of potential and the other of which is subject to a decrease of potential as the short-circuit is removed, said means being so 55 connected that the voltage impressed on such windings will decrease as the supply voltage decreases.

40. Means for controlling the reclosing of 60 an automatically reclosing circuit breaker comprising windings which are balanced against operation by such potential as is applied thereto as long as a short-circuit exists but which are unbalanced to effect operation when such short-circuit is removed to 65 a predetermined degree.

41. Means for controlling the reclosing of 70 an automatically reclosing circuit breaker comprising windings which are balanced against operation as long as a short-circuit exists regardless of fluctuation of supply voltage, but which are unbalanced to effect operation whenever such short-circuit is removed to a predetermined degree.

42. An automatically reclosing circuit 75 breaker mechanism comprising a main contact member, a means for automatically reclosing said main contact member, said means being operative in response to increase in load resistance to a predetermined 80 value but being inoperative in response to fluctuation of supplied voltage as long as said load resistance is below such predetermined value.

In testimony whereof I hereby affix my 85 signature.

ESTEL C. RANEY
